1st-Tech-Ideas(57) **CLAIM**

The ornamental design for a water toy, as shown and described.

DESCRIPTION

FIG. 1 is a front and right perspective view of a water toy showing my new design;

FIG. 2 is a front view thereof;

FIG. 3 is a rear view thereof;

FIG. 4 is a right view thereof;

FIG. 5 is a top view thereof; and,

FIG. 6 is a bottom view thereof.

The appearance within the unshaded areas forms no part of the claimed design.

The broken lines are included for the purpose of illustrating the portions of the water toy that form no part of the claimed design.

The intended use of the design is for playing in a bath or pool.
